UNITED STATES PATENT OFFICE

MURRAY ALVIN COLLINS, OF JERSEY CITY, NEW JERSEY, ASSIGNOR TO JOHNS-MANVILLE CORPORATION, OF NEW YORK, N. Y., A CORPORATION OF NEW YORK

UNDERGROUND CONDUIT SYSTEM

Application filed October 5, 1928. Serial No. 310,615.

My invention relates to an underground conduit system through which a liquid or gaseous medium is conducted or passed from one region to another.

5 In accordance with my invention, a plurality of domes or U-shaped housing members are disposed on a suitable base in end-to-end relation to form a shell or housing for one or more pipes traversed by a fluid medium.

10 Further in accordance with my invention, the aforesaid shell or housing is divided into upper and lower chambers, preferably by members or aprons disposed in end-to-end relation, the upper chamber containing a fluid-passing pipe surrounded by loose heat-insulating material.

15 More particularly, in accordance with my invention, the aforesaid base, domes and aprons are formed of cementitious material of a character resistant to the passage of moisture or water.

20 Further in accordance with my invention, the fluid-passing pipe or pipes are anchored or guided by suitable structure molded in the aforesaid base and disposed entirely within the shell or housing formed by the aforesaid domes.

25 My invention resides in the structure, arrangement and features of construction of the character hereinafter described and claimed.

30 For an illustration of some of the forms my invention may take, reference is to be had to the accompanying drawings, in which

35 Figure 1 is a side elevational view of a conduit system constructed in accordance with my invention.

40 Fig. 2 is a vertical sectional view taken on the line 2-2 of Fig. 1 and looking in the direction of the arrows.

45 Fig. 3 is a vertical sectional view of a modified form of my invention.

50 Fig. 4 is a transverse vertical sectional view taken on the line 4-4 of Fig. 5.

55 Fig. 5 is a horizontal sectional view taken on the line 5-5 of Fig. 2 and looking in the direction of the arrows.

56 Fig. 6 is a vertical sectional view taken

on the line 6-6 of Fig. 1 and looking in the direction of the arrows.

Fig. 7 is an enlarged vertical sectional view of an inspecting and venting arrangement and is taken on the line 7-7 of Fig. 1 looking in the direction of the arrows. 55

Fig. 8 is a transverse vertical sectional view illustrating a modified form of my invention.

Fig. 9 is a vertical sectional view taken on the line 9-9 of Fig. 8 and looking in 60 the direction of the arrows.

65 In accordance with my invention, a channel or trench of suitable configuration is formed in the earth and at its bottom, there is provided a base or support 1 for a shell or housing formed preferably of a plurality of dome-shaped structures 2 disposed in end-to-end relation.

70 The base 1 may be formed of any suitable material, preferably, however, and as illustrated, of waterproof concrete which, while in a plastic or semi-plastic state, is disposed in the aforesaid trench and allowed to harden or set, expansion joints, not shown, ordinarily being provided to prevent fracture of the 75 hardened mass upon change in the ambient temperature.

75 The base 1 is laid and sloped to sump drains communicating with a sewer or dry well. When thus arranged, proper disposition will 80 be made of any leakage water which may come within the conduit system. Preferably, and as illustrated, the base 1 is somewhat lower at substantially its mid-point than at its sides thereby forming a shallow trough. However, 85 the base upper surfaces are preferably substantially flat to facilitate removal of material in the event that a cave-in should occur.

90 The domes 2 likewise may be formed of any suitable material such, for example, as a mixture of cement and mortar which, while in a plastic or semi-plastic state, is performed in a mold of suitable shape, the mixture, after hardening or setting, retaining the configuration imposed by the mold. Thereafter, the 95 domes should be treated with a suitable waterproofing agent or medium, such, for example, as sulphur in which, while in a molten condition and at suitable temperature the domes may be soaked until properly impregnated. 100

It is desirable that the domes 2 be sealed to the base 1 and to this end, the latter, during the casting operation, may be provided with spaced, parallel channels for the respective dome legs, or edges, a suitable compound or agent 3, such as bituminous or asphaltum cement, sealing the joints.

As stated above, the domes 2 are disposed in end-to-end relation on the base 1 and as illustrated in Figs. 4 and 5, adjacent domes are bevelled and spaced slightly from each other, the spaces thus provided being filled with a sealing compound 4. In performing this sealing operation, it is desirable that the end surfaces of adjacent domes be primed with an asphaltic medium, or the like, after which a suitable packing or joint compound is disposed in the open space, the latter being covered with a bituminous or asphaltic cement, or equivalent, in which is embedded a sheet of fabric 5, Figs. 4 and 5, such as asbestos roofing or sheeting material, which thereafter should be treated with a suitable coating agent.

Disposed within the housing formed by the domes 2 is a pipe P through which passes the aforesaid liquid or gaseous medium. The pipe P is supported in spaced regions by suitable means, preferably of an adjustable character and, ordinarily, at sufficient height above the base 1 to provide a chamber or passageway. The supporting means, as illustrated on the drawings, comprises spaced vertically extending standards 6, embedded in the base 1 for carrying horizontal rods or members 7. In order that the members 7 may be adjusted in a vertical direction, the upper ends of the standards 6 may be bifurcated, Figs. 4 and 5, for the reception of bolts 8, or the like, each of which holds a member or block 9 in selected position along a standard 6, teeth or serrations preferably being provided to prevent slippage. The blocks 9 are recessed to provide bearings for the members 7, which preferably carry rollers 10 for supporting the pipe P.

The distance between adjacent supporting devices may be that which is suitable and desirable, such, for example, as twelve feet, 50 more or less. These supporting devices, equipped as they are with the rollers 10, freely permit longitudinal movement of the pipe P.

In lieu of the construction described above, 55 there may advantageously be utilized an arrangement by which the space within the domes 2 is divided into upper and lower chambers or passageways. To this end, there may be a dividing means provided which, as 60 illustrated, comprises a plurality of members or aprons 12 disposed in end-to-end relation and each resting on a plurality of supporting standards 13, which may be made of metal or any other suitable material and form; for 65 instance, they may consist of concrete blocks

or slabs, and in all forms they are adapted to be readily installed and removed. The aprons may also be supported by brackets carried on the standards 6 as disclosed in Fig. 8.

The aprons 12, preferably, correspond in length with the domes 2, and the joints between adjacent domes should be disposed substantially vertically above the respective joints between adjacent aprons. However, 75 it will be seen that the nature of the structure is such that the relative position and relations of the parts can be changed to suit the occasion. As disclosed by Fig. 5, they are provided with clearances for the standards 6, blocks 9 and bolts 8. The aprons may be made of concrete or any other suitable material, and in the preferred form the concrete may be rendered waterproof the same as the domes. They are spaced in such a way as to 80 provide a channel-like way, and each is provided with perforations 14 for the passage of drip water; the shape or contour of the aprons may be such that their upper faces slope or slant towards their respective perforations. 85

When the aprons 12 are utilized, as aforesaid, the heat-insulating pipe covering material 11, Fig. 3, ordinarily is omitted, and in lieu thereof the entire upper chamber within the domes 2 is filled with a mass 15 of mineral wool or asbestos or magnesia, or a combination of the above, or other suitable heat-insulating material. It may be desirable, with the construction illustrated in Figs. 2 and 4, 95 to utilize a liner 16, preferably corrugated, and of suitable sheet material, such as composition waterproof material of the nature of roofing or the like, or of sheet metal which may be copper. This liner rests upon the 100 upper ends of the standards 13 or on the apron, as may be desired, and prevents the admission of moisture to the upper chamber in case there should be a defect in one or more of the domes 2 or in the joints therebetween. 110

To control thrust or expansion movement of the pipe P, there may be utilized anchors such as illustrated in Figs. 1 and 6, each of said anchors comprising spaced standards 17, 17 of boiler plate, or the like. The lower 115 flanged ends of the aforesaid standards are embedded in the base 1 from which they extend upwardly and pass through slots or clearances in the adjacent apron 12, the upper ends of said standards having secured thereto the complementary members 18 and 19 and may be welded to the pipe P or clamped by bolts 20, or the like. Alternately, the members 18 and 19 may be utilized as a guide, in which case, the pipe P is loosely mounted 120 therewithin. Preferably, as illustrated in Fig. 1, a clamping or guiding anchor, as aforesaid, is disposed mid-way between pairs of the pipe supporting devices comprising the standards 6. 125

For the purpose that the domes 2 may be readily inspected and to provide ready access to leaks, inspection pipes and vents may be spaced suitable distances, such as thirty feet, 5 more or less, along the conduit system. Two of these inspection units are illustrated generally in Fig. 1 and in Fig. 7 their construction is more specifically shown as comprising a special nipple 21 molded into the roof of 10 one of the domes 2 and having a passage communicating with the dome interior. A pipe 22 connected to the nipple 21 by a coupling 23 constitutes a tell-tale which extends interiorly of and is embedded in a mass of concrete 24 disposed in a conduit 25 of substantial diameter. The pipe 22 may be provided 15 with a detachable cap 26 and the pipe 25 with a detachable cover plate 27. Obviously, upon removal of the cap 26 and plate 27, the 20 interior of the dome may be inspected and, in case of a substantial leak, vapor may emerge from the conduit 22 thereby visually indicating the approximate position of said leak.

25 The feature last mentioned is of particular importance when the housing formed by the domes 2 is provided with partitions or shutters 28 consisting of upper and lower companion plate members, as shown in Fig. 30 1 of suitable waterproof material, as asbestos wood, and ordinarily located substantially mid-way between the aforesaid inspection units. These partitions or shutters form a 35 number of substantially isolated chambers extending longitudinally of the aforesaid housing, in any one of which, leaking liquid or vapor may be confined, location of said leak being readily permitted through one of the inspection units. Furthermore, when 40 the aprons, in conjunction with the filler 15, is utilized, the aforesaid partitions prevent travel of moisture by capillary action between adjacent longitudinal chambers of the housing structure.

45 In accordance with a preferred form of my invention, the base 1, domes 2 and aprons 12 are constructed of waterproof cementitious material from which accurately finished parts may be fashioned, although at 50 times, other materials, such as tiles or metals may be utilized. However, the utilization of cementitious material is especially advantageous in that the aforesaid parts may be cast on the job the domes 2 being placed in position after installation of the fluid-passing 55 pipe or pipes, supports, insulation, etc.

Moreover, the utilization of cementitious material, as aforesaid, simplifies the construction and installation of the system, renders the same durable, compact, acid-resistant and lowers the cost. The system may be installed in cold weather and when installed, the absorption is much less than with the terra cotta tile installations of the prior art. 60 The anchor pits, underdrain and drainage

stone of the prior art are eliminated and the amount of insulation filling material is greatly reduced, with no decrease in insulation efficiency.

With a conduit system constructed in accordance with my invention, an uninterrupted view, for inspection purposes may be obtained from end to end thereof. By virtue of this feature, dampness of the insulating material or the passage of leakage water through any of the apron holes 14 may be readily observed.

A conduit system of the character herein illustrated is very advantageous in that it allows for various combinations with reference to pipe installations. Thus, in the form of my invention illustrated in Figs. 8 and 9, each member or bar 7 may be provided with a plurality of spaced rollers 10 for supporting a plurality of the fluid-passing pipes P which, obviously, may be of different sizes, if desired. Figs. 8 and 9 are also illustrative of a form of my invention wherein the upper chamber contains feed pipes P and the lower chamber contains return pipes P'. In 90 a construction of this character, each bar 7 and the supporting blocks 9 therefor are disposed in a more elevated position than illustrated in Fig. 2, while beneath each bar 7, there is disposed a similar bar 7' carried by 95 blocks 9', each of which is secured to a standard 6 by a bolt 8', or the like. The return pipes P' are directly supported by rollers 10' carried by the bars 7', said return pipes P' being disposed in the chamber below the 100 aprons 12 while the feed pipes P are disposed in the chamber above said aprons 12.

Furthermore, in Figs. 8 and 9, an alternative manner of supporting the aprons 12 is illustrated, this arrangement comprising 105 brackets 29 attached to the respective standards 6 by bolts 30, or equivalent. The brackets 29 on opposite standards 6 face each other and their inner free ends form an adequate support for the particular apron 12 positioned thereon. This alternative arrangement is particularly advantageous in that the aprons 12 may be vertically adjusted at will to vary the sizes of the chambers thereabove and therebeneath.

It will be observed that the aprons 12 are readily removable. Hence, the specifically different constructions illustrated in Figs. 2 and 3 may be utilized as desired without change of the base of dome structure.

Since the rollers 10 are vertically adjustable, they may readily be brought into proper relation with respect to the hereby-supported pipe, the entire length of which may 115 be disposed at a desired height due to this adjustable feature.

It shall be understood that the apparatus or structure herein shown and described is only illustrative of my invention and that

other arrangements are within the purview thereof.

What I claim is:

1. In an underground conduit system comprising a base, domes disposed on said base in an end-to-end relation, and a removable partition dividing the space in said domes into continuous upper and lower chambers, a pipe in the upper chamber surrounded with insulating material, and a pipe in the lower chamber.

2. An underground conduit system comprising a base, dome structure for said base, groups of spaced standards disposed longitudinally along said base, and members supported by said standards and forming a partition dividing the space in said dome structure into a plurality of chambers.

3. An underground conduit system comprising a base, dome structure for said base, a partition dividing the space in said dome structure into a plurality of chambers, a pipe in one of said chambers, and groups of spaced standards disposed longitudinally along said base, each standard coacting with said partition and pipe jointly for supporting them.

4. An underground conduit system comprising a base, dome structures disposed on said base in an end-to-end relation, partition members likewise disposed in an end-to-end relation and dividing the space in said dome structure into a plurality of chambers, and vertically adjustable pipe-supporting means disposed, respectively, in said chambers.

5. An underground conduit system comprising a base, dome structure for said base, groups of spaced standards disposed longitudinally along said base, supporting members adjustable along said standards, and a partition carried by said supporting members and dividing the space in said dome structure into a plurality of chambers.

6. An underground conduit system comprising a base, dome structure for said base, a partition dividing the space in said dome structure into a plurality of chambers, pipes in said chambers, and a plurality of members each coacting with said partition and pipes jointly for supporting them.

7. In an underground conduit system comprising a base, domes disposed on said base in an end-to-end relation, and a vertically adjustable partition dividing the space in said domes into continuous upper and lower chambers, a pipe in the upper chamber surrounded with insulating material, and a pipe in the lower chamber.

8. In an underground conduit system comprising a base, domes disposed on said base in an end-to-end relation, and a vertically adjustable partition dividing the space in said domes into continuous upper and lower chambers, a pipe surrounded with insulating material supported on vertically adjustable

means in the upper chamber, and a pipe supported on vertically adjustable means in the lower chamber.

9. An underground conduit system comprising a base, dome structure for said base, standards spaced longitudinally along said base, members supported by said standards and forming a partition dividing the space in said dome structure into a plurality of horizontal chambers and horizontally arranged pipe-supporting means positioned in the upper chamber and adjustably secured to said standards.

10. An underground conduit system comprising a base, dome structure for said base, standards spaced longitudinally along said base, vertically adjustable supporting members adjustably attached to said standards, a partition carried by said supporting members and dividing the space in the dome structure into a plurality of horizontal chambers, horizontally arranged pipe supporting means positioned in at least one of said chambers and adjustably secured to said standards.

11. An underground conduit system comprising a base, dome structure for said base, standards spaced longitudinally along said base, a plurality of horizontally arranged supporting means adjustably secured to each of said standards, a partition carried by certain of said supporting means and dividing the space in the dome structure into a plurality of horizontal chambers and a pipe carried by others of said supporting means.

12. In an underground conduit system for housing pipes, a plurality of pipe housing members disposed in an end-to-end relation and constituting a conduit, partition members disposed transversely in said conduit in an end-to-end relation and dividing the space therein into an upper and lower chamber, and pipe supporting rollers disposed in each of said chambers.

Signed at New York in the county of New York and State of New York this 2nd day of October A. D. 1928.

MURRAY ALVIN COLLINS.
